United States Patent Office

Des. 183,852
Patented Nov. 4, 1958

183,852

ELECTRICALLY-POWERED GOLF BAG CART

Samuel M. Marcus, Denver, Col.

Application February 15, 1957, Serial No. 44,876

Term of patent 14 years

(Cl. D14—3)

—fig. 1.

Fig. 1 is a perspective view of the electrically-powered golf bag cart;

Fig. 2 is a side view of an electrically-powered golf bag cart showing my new design;

Fig. 3 is a top plan view thereof; and
Fig. 4 is a front view thereof.

I claim:

The ornamental design for an electrically-powered golf bag cart, as shown.
